The ornamental design for a digital video camera, as shown and described.

DESCRIPTION

FIG. 1 is a front view of a digital video camera showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a front perspective view where the finder is tilted thereof.

The broken lines shown in the drawings illustrate portions of the digital video camera that form no part of the claimed design.
